UNITED STATES PATENT OFFICE.

JOHN F. HEISTER AND JOSEPH DAVIDS, OF GENEVA, NEW YORK, ASSIGNORS TO PHILLIPS & CLARK STOVE COMPANY, OF GENEVA, NEW YORK, A CORPORATION OF NEW YORK.

DESIGN FOR A STOVE.

41,750.

Specification for Design.

Patented Sept. 5, 1911.

Application filed May 8, 1911. Serial No. 626,009. Term of patent 7 years.

To all whom it may concern:

Be it known that we, JOHN F. HEISTER and JOSEPH DAVIDS, citizens of the United States, residing at Geneva, in the county of Ontario and State of New York, have invented a new, original, and ornamental Design for Stoves, of which the following is a specification, reference being had to the accompanying drawings, forming a part thereof.

The figure is a perspective view of the stove showing our new design.

We claim:

The ornamental design for a stove, as herein shown.

JOHN F. HEISTER.
JOSEPH DAVIDS.

Witnesses:

S. H. MERRILL,
H. M. MILLER.
